ARTHUR E. SPINASSE, OF MOUNT VERNON, OHIO.

BAIT FOR GLASS-DRAWING MACHINES AND IN THE PROCESS OF DRAWING GLASS.

15,143.

Specification of Reissued Letters Patent. Reissued July 5, 1921.

Original No. 1,170,464, dated February 1, 1916, Serial No. 747,581, filed February 10, 1918. Application for reissue filed December 10, 1917. Serial No. 206,543.

To all whom it may concern:

Be it known that I, ARTHUR E. SPINASSE, a citizen of the United States, residing at Mount Vernon, in the county of Knox and State of Ohio, have invented certain new and useful Improvements in Baits for Glass-Drawing Machines and in the Processes of Drawing Glass, of which the following is a specification.

10 My invention relates to the art of drawing glass and has particular relation to baits used for this purpose and to processes in which said baits are used.

One of the principal drawbacks in the 15 drawing of glass by machinery has, hitherto, resided in the danger of breakage which I may state, has been largely due to the different coefficients of the glass and the material of the bait.

20 My invention consists in a bait formed to be so operative as to eliminate this danger of breakage, especially when it is used in carrying out my process of drawing glass.

25 One of the principal drawbacks in the drawing of glass has, hitherto, resided in the breakage occurring in the formation of the initial portion of the article to be drawn, which breakage, I may state, is largely due 30 to the difference between the expansion coefficients of the glass and the material of the bait, and to variations of temperature. My invention also consists in a process of drawing so that the difficulties and breakage due to this difference are eliminated, and 35 greater drawing speed attained.

40 My invention may be best described in relation to the drawing of glass cylinders or "rollers" although it is not necessarily limited thereto.

45 Before entering into a description of the structural details of my bait, it seems practically necessary to outline the difficult situation to be met with in the drawing of glass with a bait.

It must first be clearly realized that, from the moment the draw commences, there will be either a band of glass surrounding a piece of the bait material which is usually iron; or there must be a band of iron surrounding a piece of glass. Now, with this condition necessarily existing, it must be very apparent that the application of even a uniform heat to the connected pieces of bait

and glass would change their bulks; and the 55 change in one would not correspond to the change in the other for the very apparent reason that their coefficients differ. If the material of the bait were such that its coefficient was equal to the coefficient of that 60 glass, then, under a uniform heat, the expansions and contractions would doubtless accord. But, this is with a uniformly applied heat, and furthermore any material whose coefficient approaches that of glass 65 would in all probability be too expensive.

Now, let us consider and first appreciate that the heating action is not uniform and can hardly be made so. The bait is always of a different temperature from the molten 70 glass bath into which it is inserted. This molten glass bath is generally at an approximate temperature of 1500 degrees F. Hitherto, the temperature of the bait has always been less. Consequently, there is an 75 interchange of heat between the glass and the bait during the draw, that portion of the cylinder which connects it to the bait and which is usually termed the novel yielding up its heat to the bait. This glass novel, 80 in giving up its heat to the bait, contracts. The bait, on the contrary, expands as it absorbs the heat until the temperatures of the glass novel and the bait are substantially equal. Probably the novel sets after the 85 bait has expanded considerably. Then, probably, both the novel and the bait commence to cool but one inevitably cools more rapidly than the other. This would result alone from the fact that one or the other, 90 the novel or the bait, is directly subject to the atmosphere. Furthermore, it will be apparent that neither the novel nor the bait will be individually heated with uniformity. In the first place, the edges of the 95 bait must inevitably heat more than the rest of the body. Then, the first part of the bait to enter and the last to leave the bath must absorb more heat than the rest of the bait. Then too, it is ordinarily true that 100 the edges of the bait are the first part to enter and the last part to leave the bath. Now, the difficulty generally arises after the comparatively brittle glass has set. For instance, assume that the novel has attained 105 its final form during the expansion of the bait. If the glass surrounds the bait, further expansion of such bait must break the

novel; or, if the bait surrounds the glass, the return of such bait to initial size on cooling must rupture the fragile glass because the novel has attained its final form during 5 expansion and while the bait was larger than normal. This is an exposition of the difficulties which are presented due to the variations of general contour of the bait and novel in relation to each other. It must be 10 borne in mind that these variations may seem minute to the human eye and yet may be very vital. It would be possible to enlarge upon this paragraph with little difficulty but it is thought unnecessary.

15 Local variations of the bait and novel surfaces may, under some conditions, be just as vitally important as variations of general contour. In this, I have particular reference to superficial variations which will 20 cause breakage upon the setting of the novel if the novel and bait have become fused to each other. The reason for this is very simple and very apparent. Superimposed areas 25 of novel and bait surfaces, coinciding throughout at one temperature and instant, would not coincide the instant afterward upon the slightest temperature variation. Also, as pointed out, the temperature variations are never uniform. Now, if these 30 perimposed areas of surface are fused, the tension stresses arising in the effort to tear apart will break the novel, impair the bait, or do both.

To the best of my knowledge, the above 35 analysis of the difficulties to be met with is original with me and is the result of many years of study and experiment. The basis of my invention is a recognition that the minute variations of form of the novel and bait, relatively, are material. Then, with this recognition as a basis, my invention resides in attaining a novel and bait of such relative form that the effect of the variations is nullified, thus rendering them immaterial.

40 My invention has to do with the relation of the novel and the bait from a standpoint of support and it has to do with the relation of the novel and the bait from a standpoint of form. Viewed from both standpoints, 45 my invention has to do with the production on the bait of a novel supported in what may be termed an easy relation.

The term easy relation has a broad meaning in my mind and such easy relation has 50 to be produced by the avoidance, primarily, of certain dangerous conditions existing between the bait and novel. The things to be avoided are: Fusion of bait and novel surfaces. Direct rupturing pressures due to 55 relative form. Combination of direct pressures and tension stresses. Fusion of the bait and novel surfaces must be avoided. This is best effected by using the bait comparatively cold, that is, in the neighborhood 60 of 200 degrees F. It is not improbable that

the same result might be obtained by covering the bait with graphite or some similar material.

Direct rupturing pressure due to relative form must be avoided. Herein lies my invention. My invention includes a bait of such character that, given avoidance of material fusion, it will support the novel without fusion and will automatically accommodate itself to the changes in form of the 75 novel. (In the use of the term novel I mean to include that portion of the cylinder which connects it to the bait and which may have infinite variety of form.) My invention, therefore, is a bait constructed to support 80 the cylinder by its initial portion or novel without fusion. This bait is yieldable to avoid direct rupturing pressure and in such yielding it still holds this initial portion or novel with ample firmness to permit of blowing and drawing the cylinder. Preferably 85 my bait automatically returns to normal position for successive operations.

My invention may take various forms but it preferably comprises a supporting surface 90 made up of concentrically mounted sections which may be maintained in proper position by gravity return after yielding, by inherent resiliency, or by supplemental springs or weights. The sections are sufficiently close 95 together to prevent the glass from readily flowing therebetween and they contract and expand individually, spreading and contracting in assemblage when necessary to avoid rupture of the novel. The relation 100 between the novel and the bait is essentially that of the coupling—in its broad features a car coupling—in which the coupling member of the novel or cylinder is formed by the chilling effect of the bait coupling member.

The preferred embodiments of my invention are shown in the accompanying drawings in which similar characters of reference designate corresponding parts and in which:

Fig. 1 is a section taken through one form of my improved bait showing it in the act of dipping into the molten bath just prior to drawing.

Fig. 2 is a section taken through the same bait immediately after the drawing operation has commenced, the core of the novel remaining on the surface of the bath.

Fig. 3 is a section showing the bait at a slightly subsequent period of the drawing 120 operation and after the blowing action has commenced. It will be noted that the assembled sections have slightly separated in response to conflicting pressures between the bait and novel.

Fig. 4 is a section of the same bait showing its manner of removal from the novel when the drawing operation has been completed.

Fig. 5 is a top plan view of the bait shown 130

in the preceding figures of the drawing, showing the air pipe in section.

Fig. 6 is a section of a modified form of bait wherein the sections are resiliently maintained in operative position by a washer under the control of a coil spring.

Fig. 7 is a section of a bait having hinged sections which are under the control of a washer to the extent that such washer precludes excessive spreading while the mounting of the sections gives them a natural tendency to return to operative position.

Fig. 8 is a section of another yielding bait which embodies the principles of my invention.

Fig. 9 is a section through a still different form of bait constructed in accordance with my invention.

Fig. 10 is another modification of my sectional bait wherein the sections are laterally yieldable with a sliding action.

Fig. 11 shows a form of yielding bait wherein the sections are inherently resilient and form a pocket for retaining and supporting the novel.

Fig. 11^a is a view showing another form of bait which may be of malleable metal, whereby direct rupturing stresses are avoided, and Fig. 11^a another somewhat similar view. The foregoing show in-curved lower edges or flanges about the opening for the novel.

Fig. 12 shows a bait substantially similar to that shown in Fig. 11, with the exception that the novel is to be supported upon the exterior of the bait, which shows an out-curved flange instead of within a pocket formed by the section.

In the drawings, Figs. 1 to 5, inclusive, show the bait as comprising a pipe 1 with socketed ears 2 for the support of pins 3 of gravity sections 4. These sections are mounted to have a common center and are of a form to produce a pocket for the retention and support of a novel, inasmuch as they have supporting surfaces which are substantially horizontal but for the fact that they are slightly dished at the rear to form shallow grooves with inwardly and upwardly inclined walls. Also, the orificial

walls of the sections are desirably rounded or given a gradually outward sweep, while the adjacent exterior surfaces of the sections are formed to shed the glass with which they come in contact. Each section may be provided with a handle 5. The sections are so hingedly supported that they naturally assume such relative positions as to form a pocket with slightly concaved novel supporting surfaces and with the remaining surfaces free of restraining abutments or projections. The operation of this form is probably best made clear by reference to Figs. 1, 2, 3 and 4, successively. Fig. 1 shows the bait in the normal position of its parts. Inasmuch as I preferably use the

bait while at an approximate temperature of 200 degrees F., or less the exchange of heat between the glass and the bait has already begun.

Fig. 2 shows the bait immediately after the drawing operation has commenced, at which time the position of the bait sections in relation to each other has not noticeably changed. Fig. 3 shows the bait after the drawing has progressed somewhat, it being noted that the sections have separated in yielding to avoid rupturing the novel. The comparative sizes of the slots 6 is indicative of what has taken place, and although the change of position is apparently slight, it is just sufficient to avoid the rupturing pressure which would otherwise have arisen. Fig. 4 shows the manner of removing the novel from the bait. It will be apparent that this is effected by separating the sections and that it therefore becomes unnecessary to break the novel. That this is a distinct advantage, will be appreciated by workers in the art who have observed that the breaking of the novel on the bait frequently causes impairment of such bait.

Broadly my improved method comprises conditioning my bait so that it may form a novel without fusion of bait and novel surfaces and so that it will not rupture a novel because of differential expansion and contraction during the drawing process, dipping the bait into a glass bath in such condition to a depth indicated in Fig. 1, for a time sufficient to procure the novel, and then withdrawing the bait, supporting the hollow novel upon its interior, without fusion of bait and novel surfaces. Withdrawal is effected while preferably introducing air under pressure within the bait and the hollow novel as the bait is elevated, so as to expand the depending portion of glass or novel while formable during its cooling, to form a cap or shoulder A beneath the bait. From the base of said shoulder, when sufficiently cooled, the regular cylinder is drawn, suitable air under pressure being supplied to its interior.

In the use of my present bait in the process of drawing glass cylinders from a glass bath as herein described, I first form an expanded cap or shoulder from a glass bath, said cap supported by its initial portion or novel non-adherent and free from rupturing strains upon the bait interior. I am therefore able to produce very large cylinders from the shoulder, by the use of a bait of this kind comparatively small with respect to the cylinder being drawn; this is important because in a process of this kind the differential expansion and contraction between the bait and novel increase materially as the bait and therefore the novel, increase in diameter. I prefer to blow my cap or shoulder at once. By the words "at once" 130

where they appear, I mean, while the glass is still formable and gradually cooling, and within a time and drawing speed such as to obtain sufficient thickness of wall in the 5 novel and shoulder formed, to properly support the cylinder during the drawing process, I thus save time and obtain a longer cylinder of better quality, thus increasing the production very materially. In my present 10 invention I use a bait of such weight and construction as to form and support the shoulder without fusion of its initial portion or novel to the bait, but preferably in resilient firmness, therefore effecting a still 15 further saving of glass because I avoid the jars and strains incident to the use of a loose novel during the drawing process, the formable glass of the novel and shoulder being formed by the inner air pressure introduced, 20 so as to permit this.

The form of bait shown in Fig. 6 comprises a pipe 7, sections 8 hinged as at 9 to ears 10 and a means for resisting and finally limiting the outward swinging of these 25 sections upon their hinges or pivots. This means is in the form of an inverted cup-shaped washer 11 which surrounds the pipe 7 and is normally forced downwardly by a coil spring 12.

30 Fig. 7 shows a bait comprising a pipe 13 and sections 14 hinged to ears 15. Superposed above the sections and exercising an ultimate restraint upon their yielding movements is a washer 16 having its edge downwardly turned as at 17 and terminating just above the sections and at such a distance therefrom as to give them some slight capability of yielding and yet prevent too great a spreading. This washer may be held in 35 place by a pin 18 which extends through the pipe 13 immediately thereover.

Fig. 8 is illustrative of a feature which, aside from the obviation of breakage, is probably the most vital result of my improvement, that is the ability to draw the 45 cylinder without the initial forming of a neck and permitting it to set. In actual practice, this forming of the neck and permitting it to set has hitherto occupied a very 50 material part of the complete drawing period. With my yielding bait this neck, which was necessarily formed in all non-yielding baits, need not be formed. Now, in this figure, it will be seen that the sections 19 are in the form of hooks terminating in upwardly and inwardly directed wedges 20 whose lower surfaces 21 have a gradually downward and outward trend. 55 Immediately after the novel is secured, its 60 depending portion may be blown outwardly into contact with the surface 21. It is not necessary or advisable to await forming and setting of any neck.

Fig. 9 shows a still further possibility of 65 my invention which arises from the ability

to do away with both the neck and the cap which have always, hitherto, been formed preliminary to the actual forming of the cylinder. (This cap which is eliminated is well exemplified at A in Fig. 3). It will be 70 seen that there remains only the novel to connect the cylinder to the bait and that the diameter of the cylinder is substantially equal to the inner diameter of the bait. This bait is also of unusual advantage because of the increased area of the surfaces which come in contact with the glass bath and which serve to more effectually chill the 75 glass. However, the sections may vary as to form.

Fig. 10 represents a bait in which the pipe carries a disk-like flange 22 on its lower end, the upper surface of such flange supporting sections 23 of hook-like form and producing a pocket structure when assembled. These 80 sections are freely slideable upon the flange 22 except for the restraint of a weighty washer 24 having a conical socket 25 which embraces and rests upon wedge-like formations 26 upon the inner ends of the sections. 85 It will be apparent that this weighty washer tends to maintain the sections in their normally indrawn positions but that they may spread under radially outward pressure. In 90 operation, this is just what happens and the 95 danger of direct rupturing is obviated.

Figs. 11 and 12 show forms of yielding baits whose yielding action is attained through the inherent resiliency of fingers which correspond to the sections in the other forms described. In both forms, the pipe 100 27 carries an integral formation comprising resilient fingers 28 and the action will be apparent.

In summary, my invention consists in the 105 provision of an improved form of bait which is such that direct rupturing pressures are avoided for the reason that, since the novel will not yield after it has once set, the bait automatically yields and varies its form to 110 sufficiently avoid all conflicts which threaten to rupture either the bait or novel.

I have indicated a yielding bait, which bait may be used of relatively large proportions and will properly sustain the full 115 weight of a cylinder drawn. By the term "yielding" as applied to my bait in my specification and claims, I mean a bait of such form and weight that it may form and support a novel without becoming so heated 120 as to cause adhesion of the bait and novel surfaces, and so that it will not rupture a novel because of differential expansion and contraction during the drawing process.

I believe that I am the first to use a bait 125 of this character which in general has an incurved ledge or flange ending at a glass admitting opening in the bottom thereof so as to provide an interior support such that it may form and support the initial portion 130

or novel of a cylinder drawn, in easy relation throughout the drawing process, the flange or support being preferably of greater weight and thickness toward the bottom of the bait, the bait being provided with means to introduce air under pressure therein and into the cylinder being drawn during the drawing process.

I have shown a number of forms of bait each constructed to form and support a novel without fusion and without causing rupturing strain. It will be understood, however, that many modifications are possible without departing from the spirit of this invention. In my drawing process by the use of said bait, I so form the novel and cap or shoulder, that avoidance of strain and rupture by one to the other is assured. To procure the novel without adhesion of bait and novel surfaces, I have indicated using the bait at a relatively low temperature or covering the bait with graphite or the like, however, I do not wish to restrict myself to these as the conditioning of the bait may possibly be effected in similar or equivalent other ways, my aim being to prevent the bait from adhering to the glass during the drawing and to avoid rupturing stresses and to avoid rupturing stresses.

I do not limit myself to the forms of baits shown, since a malleable metal bait might serve. See Figs. 1^a and 11^a. However, the scope of my invention is set forth in the appended claims.

Having thus described my invention, what I claim as new and desire to cover by Letters Patent is:

1. A bait for drawing glass comprising a continuous element constructed to vary its form in avoidance of relatively rupturing pressures, said element being so constructed that the novel may be supported without fusion and may be so formed in relation to said element that it will not interfere with the said variation of form.

2. A bait for drawing glass comprising a continuous element having yieldable sections, said element being so constructed that the novel may be supported without fusion and may be so formed in relation thereto that it will not interfere with the yielding of said sections.

3. A bait for drawing glass comprising a continuous novel-supporting element having sections yieldable at the point of departure of the novel from the bait, said element being so constructed that the novel may be supported without fusion and may be so formed in relation to said element that it will not interfere with the yielding of said sections.

4. A bait for drawing glass comprising a continuous novel-supporting element having sections capable of a substantially horizontal yielding action, said element being so constructed that the novel may be supported

without fusion and may be so formed in relation thereto that it will not interfere with the yielding of said sections.

5. A bait for drawing glass comprising sections assembled to produce a pocket 70 adapted to support a novel without fusion, said sections being continuous and being yieldable to render the walls of the said pocket automatically adjustable.

6. A bait for drawing glass comprising 75 sections pivoted in assemblage at their upper ends and normally disposed to produce a surface adapted to support a novel without fusion, said sections forming a continuous bait and being capable of swinging on their 80 pivots sufficiently to accommodate variations of the relative forms of the novel and bait.

7. A bait for drawing glass comprising sections pivoted in assemblage to form a pocket of a contour to support a novel without fusion, said sections forming a continuous bait and being capable of swinging on their pivots sufficiently to avoid rupturing pressures between the bait and the novel supported within its pocket. 90

8. A bait for drawing a glass cylinder comprising a continuous element constructed of yielding parts and adapted to support a novel and at the same time yield to avoid rupturing pressures, said bait having a contour to permit immediate blowing of the cylinder whereby the glass may be blown outward against said yielding parts without locking the bait against its yielding action. 95

9. A device for drawing glass comprising 100 a hollow bait with inwardly extending fingers, provision being made in the bait whereby expansion or contraction of the bait and novel with reference to each other may be converted into a modification of the shape of 105 the bait with reference to the novel, without the development of constrictive pressure upon the novel.

10. A bait for drawing glass comprising a hollow continuous element having yielding 110 sections, said element being so constructed that when the novel is supported without fusion, expansion and contraction of said novel with reference to the bait may be taken care of without the development of rupturing strains or pressures between the novel and the bait. 115

11. A hollow continuous bait for drawing glass cylinders, said bait being made in 120 yieldable sections.

12. A hollow continuous bait for drawing glass cylinders, said bait being continuous and consisting of sections pendant at the top and inwardly curved at the bottom, whereby upon expansion of a novel said sections may 125 yield outwardly.

13. A bait for drawing glass cylinders consisting of an air pipe, a head mounted on the end of said air pipe, and bait sections pivoted on said head, said sections being in- 130

wardly curved and continuous at their bottom so as to form a bait narrower at its lower end than at its interior, whereby when a novel is formed, expanding stresses may be converted into an outward push of the novel head upon the bait, whereby the sections of said bait are made to swing outward or diverge without rupturing effect.

14. A bait for drawing glass cylinders 10 consisting of a pipe whereby air may be introduced into the interior of said cylinders, ears secured upon the lower end of said pipe, bait sections pivoted upon said ears, and pendant from said pivots, and turned inward at their bottom so as to form a continuous edge for the bait, the line of said edge being outside or forming a larger circle than the line of pivots whereby the weight of said sections always tends to draw them 20 together at the bottom.

15. A hollow bait made up of yieldingly supported parts and having a substantially horizontal ledge for supporting the lip of a free novel.

16. A hollow bait made up of yieldingly supported parts and having a bottom opening and an interior substantially horizontal ledge surrounding said opening.

17. A bait for drawing glass comprising 30 means for firmly supporting without adhesion a glass novel, said means being adapted to prevent rupturing strains in said glass which would otherwise occur on account of differences in expansion and contraction of 35 said bait and said novel relative to each other.

18. A hollow bait for drawing glass having 40 a source of fluid pressure connected therewith and a substantially continuous internal ledge extending substantially horizontally or above the horizontal and surrounding a central opening in the bottom of the bait.

19. A hollow bait for drawing glass having 45 an internal ledge surrounding a central orifice in the bottom thereof, said ledge being rounded and thickened at its inner edge to prevent fusion of the surface thereof to the glass.

20. A bait for drawing glass shaped to 50 support a glass novel and provided with means for preserving a fixed relation between the glass contacting surface thereof and that of said novel without fusion of 55 said surfaces to each other.

21. The process of drawing glass articles by dipping into molten glass a bait adapted 60 to form and lift a glass novel without adhesion and to compensate for different relative expansion and contraction of the glass and bait in order to avoid constrictive rupturing pressures, and then proceeding with the blowing and formation of the article before the bait engaging portion of the glass 65 is set.

22. The process of drawing glass cylinders comprising dipping into molten glass a bait adapted to accommodate itself to changes in form of the novel during drawing and at a temperature to form and lift 70 the novel without adhesion, and then before the bait engaging portion of the glass is set proceeding with the blowing to form a novel expanded to fit closely the orifice of the bait and to form a cap of greater diameter 75 than that of the bait and drawing the cylinder under distending air pressure.

23. A bait for drawing glass cylinders, 80 said bait having means for supplying fluid pressure to form a glass cylinder, said bait having supporting means of sufficient mass to form, cool and lift a glass novel from molten glass without adhesion between the bait and the contacting surface of the glass therewith.

24. A bait for drawing glass adapted to be used at a temperature below that at which glass will adhere therewith comprising means for supplying distending air thereto for expanding the hollow drawn glass or 90 cylinders, said bait having a bottom orifice and an interior portion thereabove for supporting a novel, the glass engaging walls of said bait being of smaller diameter than that of the cylinder, and of sufficient mass 95 to form, cool and lift a novel from molten glass without adhesion between the engaging bait and glass surfaces, said bait being constructed to maintain constant relation 100 between the novel and bait without rupturing stress of the bait on the novel during the drawing operation.

25. A bait for drawing glass adapted to be used in connection with a fluid supply for blowing drawn glass or cylinders, said 105 bait comprising a glass engaging portion of smaller diameter than that of the cylinder, said bait having a central orifice in its bottom and a ledge having an upper horizontal surface surrounding said orifice, said bait being of sufficient mass so as to form, cool and lift a glass novel from molten glass without adhesion between the bait and the contacting surface of the glass therewith.

26. A bait for drawing glass adapted to 115 be used in connection with a fluid supply for blowing drawn glass cylinders, said bait comprising a glass engaging portion of smaller diameter than that of the cylinder, said bait having a central glass admitting 120 orifice in its bottom with an interior horizontal ledge surrounding said orifice and an external surface adjacent said orifice for shedding glass, said bait being of sufficient mass so as to form, cool and lift a glass 125 novel from molten glass without adhesion between the bait and the contacting surface of the glass therewith.

27. A bait for drawing glass adapted to 130 be used in connection with a fluid supply for

blowing drawn glass cylinders, said bait comprising a glass engaging portion of smaller diameter than that of the cylinder, said bait having a central glass admitting 5 orifice in its bottom and an interior portion surrounding said orifice, said bait being of sufficient mass so as to form, cool and lift a glass novel from molten glass, without adhesion between the bait and the contacting 10 surface of the glass therewith, said bait being constructed so as to press and firmly hold the novel and so as to automatically accommodate itself to the changes in form of the cooling novel.

15 28. A bait for drawing glass adapted to be used in connection with a fluid supply for blowing drawn glass cylinders, said bait comprising a glass engaging portion of smaller diameter than that of the cylinder, 20 said bait having a central glass admitting orifice in its bottom with an interior substantially horizontal ledge surrounding said orifice and an external surface adjacent said orifice for shedding glass, said bait being of sufficient mass so as to form, cool and lift a glass novel from molten glass without adhesion 25 between the bait and the contacting surface of the glass therewith, said bait being constructed so as to press and firmly hold the novel and so as to automatically 30

accommodate itself to the changes in form of the cooling novel.

29. A bait for drawing hollow glass or cylinders from molten glass comprising means for supplying distending air pressure thereto, and means for forming and lifting without adhesion a glass novel, said means being adapted to support said novel without producing rupturing strain thereon during the drawing operation. 35

30. In the drawing of hollow glass or cylinders from molten glass, a bait having a smaller diameter than that of the cylinder to be drawn, and having an exterior surface gradually converging to an orifice in the bottom of the bait and an interior portion thereabove adapted to support a novel, said bait being constructed to retain fluid pressure supplied within the hollow glass or cylinder drawn sufficient to expand and form 50 said hollow glass or cylinder, and having its walls so arranged and of such mass to form, cool and lift a glass novel without adhesion at any point between the engaging bait and glass surfaces and without rupturing stress 55 of the bait on the novel during the drawing operation, and means for supplying distending fluid pressure within the hollow glass or cylinder being drawn by said bait.

ARTHUR E. SPINASSE.
